UNITED STATES PATENT OFFICE.

ROBERT L. LYONS, OF BOSTON, MASSACHUSETTS.

THREAD-CUTTING DEVICE FOR SEWING-MACHINES.

961,509.

Specification of Letters Patent. Patented June 14, 1910.

Application filed December 23, 1907. Serial No. 407,618.

To all whom it may concern:

Be it known that I, ROBERT L. LYONS, of Boston, in the county of Suffolk and State of Massachusetts, have invented certain new and useful Improvements in Thread-Cutting Devices for Sewing-Machines; and I hereby declare that the following is a full, clear, and exact description of the same, reference being had to the accompanying drawings, forming part of this specification:

This invention relates to improvements in thread cutting devices for sewing machines and particularly to improvements in such devices for cutting the shuttle thread.

15 The object of the invention is to so construct a sewing machine having a thread cutter that the undue drawing out of the under thread may be prevented.

Another object of the invention is to lock 20 the shuttle bobbin from movement.

The invention consists in the combination with a sewing machine having a cutter against which the shuttle thread may be drawn, to cut said thread, of means for limiting the drawing out of the shuttle thread.

The invention consists in such other novel features of construction and combination of parts as shall hereinafter be more fully described and pointed out in the claims.

30 Figure 1, represents an end view of a sewing machine, partially in section, illustrating this improvement. Fig. 2, represents a sectional view of parts of the same taken on line 2—2 Fig. 1. Fig. 3, represents a sectional detail view of parts thereof. Fig. 4, represents diagrammatically, the straining of the shuttle thread over the edge of the cutter.

40 Similar numbers of reference designate corresponding parts throughout.

As shown in the drawings in its preferred form 5 indicates the head of any well known sewing machine having the bed plate 6 furnished with the throat plate 7 having the 45 needle hole 8 and the slot 9 extending from said needle hole and supplied with the cutter 10. In bearings of the bed plate 6 is journaled the shaft 11 of the shuttle carrier 12 furnished with the bobbin 13 and designed 50 to be driven in any usual manner. In said shaft 11 is formed a longitudinal bore, located eccentric of the axis of said shaft, in which is slidably mounted the spring retracted rod 14 bearing at one end against a portion of the bobbin 13 and at the other 55 end against the presser plate 15 adjustably

mounted on the cam arm 16 which is pivotally mounted on the bracket 17, extending from a part of the bed plate, and is furnished with the cam 18.

60 Pivotaly mounted on the head 5 is the lever 19 which is pivotally connected with the usual presser foot lifter rod 20, slidably mounted in the head 5 and connected with the presser which, in the machine shown 65 herein, is the button clamp 21.

Mounted to slide in a perforation formed in the bed plate 6 is the rod 22 which has at its lower end the cam 23, bearing against the cam end 18 of the arm 17, and pivotally 70 connected at its upper end with the lever 19. On this rod 22 is the stop 24 against which the spring 25 acts to retract the rod 22 when said rod is relieved from the downward pressure of the lever 19.

75 After the completion of the sewing operation the outer end of the lever 19 is depressed in any usual manner to raise the presser foot. This movement of the lever 19 depresses the cam 23 which acts against 80 the cam end 18 of the arm 16 to swing said arm and press inward the rod 14 against the action of its spring whereby the inner end of said rod engages the bobbin 13 and prevents the rotation of the bobbin and the 85 paying out of the thread thereon. When now the work A is drawn outward the thread B is drawn through the slot 9 of the throat plate 7 and becomes tight as the 90 length of the slack thread is reached until this thread is drawn against the cutter 10, as shown in Fig. 4 of the drawing when the tightened thread is cut by said cutter.

95 This invention is not necessarily limited to the particular bobbin herein shown nor to the specific means for restraining the drawing out of the thread from the bobbin for it is apparent that the object of the invention may be accomplished by any means which will resist the movement of the bobbin 100 thread so that such thread may be tightened.

Having thus described my invention I claim as new and desire to secure by Letters Patent.

1. A sewing machine comprising a rotatable bobbin, slidable means for engaging the bobbin to prevent its rotation, the presser foot actuating lever, and means operated by the movement of said lever for moving said slidale means into engagement with the 105 bobbin.

2. In a sewing machine the combination

with the bobbin shaft rotatably mounted and having a longitudinal bore, the bobbin on said shaft, and a spring retracted bobbin engaging rod slideable in the said bore of the bobbin shaft, of the presser foot actuator and means operated by the movement of said actuator for moving said bobbin engaging rod into engagement with the bobbin, for the purpose described.

10 3. A sewing machine comprising a bobbin movably mounted, means for restraining the movement of the bobbin to prevent the paying out of thread, presser foot actuating means, and mechanism operated by or through said presser foot actuated means for operating said restraining means.

15 4. A sewing machine comprising a bobbin movably mounted, means for restraining the

movement of the bobbin, presser foot operating means, and means for actuating said 20 restraining means simultaneously with the operation of the presser foot operating means.

5. A sewing machine comprising a throat plate having a needle hole and a slot extending from said needle hole, a button clamp for holding a button above said needle hole, a bobbin movably mounted below said needle hole, and operative means for positively holding said bobbin whereby 30 the drawing forward of the work effects the straining of the bobbin thread.

ROBERT L. LYONS.
